UNITED STATES PATENT OFFICE.

ANDREW W. ANDERSON, OF CHICAGO, ILLINOIS.

LOCOMOTIVE-SUPERHEATER.

1,113,731.

Specification of Letters Patent. Patented Oct. 13, 1914.

Application filed April 5, 1912. Serial No. 688,620.

To all whom it may concern:

Be it known that I, ANDREW WILLIAM ANDERSON, a citizen of the United States, residing at Chicago, in the county of Cook 5 and State of Illinois, have invented certain new and useful Improvements in Locomotive-Superheaters, of which the following is a specification.

My invention relates in general to locomotive superheaters, and more particularly to superheaters of the smoke-tube type for locomotives.

My present invention consists in improvements in superheaters of the character 15 covered by Patent No. 1010107, granted to me November 28, 1911. In the superheater specifically disclosed in my said patent, the wet steam chamber, which communicates with the steam supply, and the superheated 20 steam chamber which communicates with the cylinder steam chests, are formed in an integral casting with each other and with depending headers, the alternate ones of which communicate with the wet steam 25 chamber and the intermediate ones with the superheated steam chamber.

In my present invention, the wet steam chamber is formed in an integral casting with the headers communicating therewith 30 and depending therefrom, while in a separate casting are formed the superheated steam chamber with the headers communicating therewith and depending therefrom.

My present invention also comprises other 35 improvements in superheaters of the type covered by my said patent, which will hereinafter be fully described and specifically pointed out in the claims.

My invention has for its object to provide 40 a superheater for locomotives which may be economically constructed, conveniently assembled in the smoke-box of a locomotive, which will be simple in arrangement, inexpensive in maintenance, efficient 45 in operation, and will interfere to a minimum degree with the boiler and smoke-box.

In the accompanying drawings, in which 50 I have illustrated my invention as embodied in a convenient and practical form—Figure 1 is a central vertical longitudinal section through my superheater and the adjacent portions of a locomotive; Fig. 2, a vertical sectional view through the wet and superheated steam chambers, removed from 55 the locomotive; Fig. 3, a vertical transverse section on line 3—3, Fig. 1, portions of the

superheater being shown in elevation and the boiler shell being omitted; and Fig. 4, a plan and horizontal sectional view of the castings in which are formed the wet and superheated steam chambers, removed from 60 the locomotive.

The same reference characters are used to designate the same parts in the several figures of the drawings.

Reference letter A indicates the shell of a locomotive boiler, and B indicates the front flue sheet of the boiler through which extend the fire flues C.

D indicates the smoke-stack, while E indicates the exhaust nozzle leading from the engine cylinders.

F indicates the steam supply conduit leading from the throttle valve.

The above described structure is that of 75 an ordinary locomotive and does not in itself constitute my invention, it being shown in order that the position of my improved superheater may be fully disclosed.

G indicates a casting having an integral 80 elbow conduit H which is connected with the steam supply conduit F. In this casting are formed a horizontal wet steam chamber K and a series of spaced depending headers K' which communicate at their upper ends with the interior of the chamber K. Any suitable means may be provided for securing a steam-tight union between the elbow conduit H and the steam supply conduit F, such, for instance, as a flange h 85 surrounding the end of the elbow H, which is bolted to a ring f surrounding the conduit F and located inside of the flue sheet B. A gland F' surrounds the end of the conduit F and is clamped between the ring 90 f and flange h, the engaged surfaces of the gland and end of the elbow H being preferably beveled, as shown in Fig. 1, to insure a tight joint. The casting G is located in the smoke-box of the locomotive in 95 such position that the chamber K lies slightly above the top row of the boiler flues.

J designates a second casting in which are 100 formed a horizontal chamber L for the superheated steam and which communicates with the steam chests of the engine cylinders, and a series of spaced depending headers L', said headers being arranged in alternate positions relatively to the headers 110 K' which depend from the wet steam chamber K. The headers are shown as nine in

number, five of which depend from the wet steam chamber and four from the superheated steam chamber. The headers are staggered with respect to the vertical planes 5 of the series of boiler flues C, as will be clearly seen by reference to Fig. 3. The adjacent headers K' and L' are placed in communication with each other through the medium of a plurality of vertical series of 10 coils M, which extend within the boiler flues C, each of the vertical series of coils M preferably consisting of four coils, as shown in Figs. 1 and 3, and as fully disclosed in my said Patent No. 1010107. One end m' of 15 each of the coils M extends through an opening in the rear wall of one of the headers K', while the opposite end m² of the coil M extends through an opening in the rear wall of the adjacent header L', so that each of 20 the coils M connects a header depending from the wet steam chamber with a header depending from the superheated steam chamber.

The surfaces of the various headers to 25 which the coils are connected are preferably stepped vertically, as shown in Fig. 1, while the front surface of each header is provided with plugs r, closing holes alining horizontally with the ends of the steam coils. The 30 lower coils in each of the several vertical rows extend through flues located in a plane below the bottoms of the headers, as shown in Fig. 1, thereby securing the increased capacity due to four coils in each vertical series, without necessitating the headers being 35 projected downwardly so far as to necessitate the too great lowering of the automatic damper mechanism, which blocks the draft through the boiler flues for preventing the 40 burning out of the coils when steam is not passing through them.

R' R² indicate two horizontally pivoted dampers, the former of which is fixed to an oscillating rod r' and the latter to an 45 oscillating rod r². The damper mechanism need not be further described hereinafter, as it is fully set forth in my said patent, and forms no part of my present invention.

P designates a partition which separates 50 the space within which the superheater is located from the rest of the smoke-box, the lower part of which is removable to permit access to the headers and superheated coils.

The headers K' which depend from the 55 wet steam chamber are offset forwardly below the plane of said chamber, so as to extend beneath the superheated steam chamber L, as will be clearly seen in Fig. 1, while the headers L' which depend from the superheated steam chamber L are offset, so that 60 they project beneath the wet steam chamber. By this arrangement the wet and superheated steam chambers may be located in close relation and the headers may occupy 65 the same transverse plane. The casting in

which the superheated chamber is formed is supported upon the casting in which is formed the wet steam chamber, by means of ears l' and l² projecting outwardly from the ends of the casting J and having enlarged openings therethrough surrounding stdus l' and l² supported through screw threaded engagement with the adjacent wall of the casting G. The casting G is supported within the smoke-box of the locomotive, both through the connection of the elbow coupling H with the end of the steam supply conduit, and by means of brackets g' and g² which project outwardly from the ends of the casting and rest upon suitable brackets a' and a², respectively, secured to the boiler shell. The opposite ends of the superheated steam chamber L communicate with conduits o leading to the cylinder steam chests, such conduits being connected to the 80 casting J by means of bolts n passing through registering holes in the flanges N and O formed around the communicating openings in the upper ends of the conduits o and adjacent ends of the casting J. 90

In the operation of my improved superheater, the steam passes from the conduit F when the throttle valve is open to the wet steam chamber K, thence downwardly through the depending headers K', through 95 the vertical series of horizontal coils, back to the headers L', thence to the superheated steam chamber L from which the superheated steam passes through the conduits o to the respective steam chests of the engine 100 cylinders.

By my present improvements, the advantages fully set forth in my said Patent No. 1010107 may be attained, and at the same time the wet and superheated steam chambers and headers depending therefrom may be more economically made and assembled by reason of the fact that they are made in two separate castings. It will be observed that the casting in which the superheated steam chamber and headers depending therefrom are formed is yieldingly supported upon the casting in which the wet steam chamber is formed, so as to permit the two castings to relatively move to compensate for differences in expansion and contraction due to differences in temperature. 110

I claim:

1. In a superheater for locomotives, the combination with a casting comprising 120 therein a wet steam chamber connected to the steam supply and headers depending from and communicating with said chamber, of a second casting comprising therein a superheated steam chamber connected to the cylinder steam chests and headers depending therefrom in alternate relation to the headers depending from the wet steam chamber, means for yieldingly connecting said castings, and superheating coils located in the 125 130

boiler flues, each coil being connected at one end to a header depending from the wet steam chamber and at its other end to an adjacent header depending from the super- 5 heated steam chamber.

2. In a superheater for locomotives, the combination with a casting comprising therein a wet steam chamber connected to the steam supply and headers depending 10 from and communicating with said chamber, of a second casting comprising therein a superheated steam chamber connected to the cylinder steam chests and headers depending therefrom in alternate relation to the headers 15 depending from the wet steam chamber, the headers depending from the wet steam chamber being offset and underlying the superheated steam chamber, means for supporting said second casting upon said first casting, and superheating coils located in the boiler flues, each coil being connected at one end to a header depending from the wet steam chamber and at its other end to an adjacent header depending from the super- 25 heated steam chamber.

3. In a superheater for locomotives, the combination with a casting comprising therein a wet steam chamber connected to the steam supply and headers depending 30 from and communicating with said chamber, of a second casting comprising therein a superheated steam chamber connected to the cylinder steam chests and headers depending therefrom in alternate relation to the headers 35 depending from the wet steam chamber, the headers depending from the wet steam chamber having projecting portions which underlie the superheated steam chamber and the headers depending from the superheated 40 steam chamber having projecting portions underlying the wet steam chamber, and superheating coils located in the boiler flues, each coil being connected at one end to a header depending from the wet steam chamber and at its other end to an adjacent header depending from the superheated 45 steam chamber.

4. In a superheater for locomotives, the combination with a casting comprising 50 therein a wet steam chamber connected to the steam supply and headers depending from and communicating with said chamber, of a second casting comprising therein a superheated steam chamber connected to the cylinder steam chests and headers depending 55 therefrom in alternate relation to the headers depending from the wet steam chamber, brackets projecting from said first casting for supporting the same upon the boiler

shell, means for supporting said second casting upon said first casting, and superheating coils located in the boiler flues, each coil being connected at one end to a header depending from the wet steam chamber and at its other end to an adjacent header depending from the superheated steam chamber. 60

5. In a superheater for locomotives, the combination with a casting comprising therein a wet steam chamber connected to the steam supply and headers depending 70 from and communicating with said chamber, of a second casting comprising therein a superheated steam chamber connected to the cylinder steam chests and headers depending therefrom in alternate relation to the headers 75 depending from the wet steam chamber, brackets projecting from said first casting for supporting the same upon the boiler shell, ears projecting from said second casting, studs supported by said first casting and passing through enlarged holes in said ears for supporting said second casting upon said first casting, and superheating coils located 80 in the boiler flues, each coil being connected at one end to a header depending from the wet steam chamber and at its other end to an adjacent header depending from the superheated steam chamber. 85

6. In a superheater for locomotives, the combination with a casting comprising 90 therein a wet steam chamber connected to the steam supply and headers depending from and communicating with said chamber, of a second casting comprising therein a superheated steam chamber connected to the 95 cylinder steam chests and headers depending therefrom in alternate relation to the headers depending from the wet steam chamber, the headers depending from each chamber being offset to project beneath the other 100 chamber whereby said headers lie in the same transverse plane relatively to said locomotive, means for detachably supporting said second casting upon said first casting, whereby relative movement of said castings 105 owing to unequal expansion thereof is permitted, and superheating coils located in the boiler flues, each coil connected at one end to a header depending from the wet steam chamber and at its other end to an adjacent 110 header depending from the superheated steam chamber.

In testimony whereof, I have subscribed my name.

ANDREW W. ANDERSON.
